US0D1074772S

(12) **United States Design Patent** (10) **Patent No.:** **US D1,074,772 S**
(45) **Date of Patent:** **** May 13, 2025**

(54) **WELDING DEVICE**

(71) Applicant: **Illinois Tool Works Inc.**, Glenview, IL (US)

(72) Inventors: **Nathan Joe Jochman**, Neenah, WI (US); **Logan Mathew Vandecorput**, Glenview, IL (US)

(73) Assignee: **Illinois Tool Works Inc.**, Glenview, IL (US)

(**) Term: **15 Years**

(21) Appl. No.: **29/858,414**

(22) Filed: **Oct. 31, 2022**

(51) **LOC (15) Cl.** **15-09**

(52) **U.S. Cl.**

USPC **D15/144**

CLAIM

The ornamental design for a welding device, as shown and described.

DESCRIPTION

FIG. 1 is a front perspective view of a welding device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures depict portions of the welding device that form no part of the claimed design.

1 Claim, 7 Drawing Sheets
